APPARATUS FOR DIRECTING GUNS

Robert F. Garbarini, Woodside, and Willis G. Wing, West Hempstead, N. Y., assignors to Sperry Gyroscope Company, Inc., Brooklyn, N. Y., a corporation of New York

Application March 1, 1943, Serial No. 477,664

13 Claims. (Cl. 235—61.5)

1

The present invention relates to the art of directing gun fire against a moving target, and particularly to means for, and methods of, directing guns against rapidly moving targets such as aircraft.

In view of the many factors entering into the prediction of future position of moving targets, the accuracy of gun directors depends to a large extent upon the complexity of the mechanism used.

Examples of prior directors may be found in Patent No. 2,065,303, for Apparatus for the control of gunfire, issued December 22, 1936, in the names of E. W. Chafee, H. Murtagh and S. G. Myers; copending application Serial Number 434,090, for Anti-aircraft gun directing system, filed March 10, 1942, in the names of E. W. Chafee, C. G. Umstead, and L. C. Warner, and copending application Serial Number 470,686, for Gun directing apparatus, filed December 30, 1942, in the names of D. J. Campbell and W. G. Wing.

These directors have been developed, primarily, for use in connection with relatively long range guns capable of protecting a comparatively large area. In order to obtain accurate predictions of the future positions of a target, these directors are of a complex nature, and their manufacture involves considerable amounts of time and materials. There is also a certain delay between the time a target is first sighted and the time that accurate predictions are furnished by the director for positioning guns to fire against the target. This delay is not of sufficient length to curtail the effectiveness of the directors when used for relatively long ranges. In the case of shorter range guns, it will readily be seen that a rapidly moving target might move out of range during the time required for these directors to supply accurate predictions of the future position of the target.

As is well known, gunsights, with or without comparatively simple prediction mechanisms are sufficiently accurate to direct the fire of relative short range guns. For these short ranges, even high speed targets cannot move a very great distance between the time a projectile leaves the gun and the time it reaches the target. Hence, small errors in the aim of the gun may not cause it to miss a target completely. In addition, the operator of a short range gun may easily make corrections in the aim of the gun on the basis of the accuracy of previous fire.

From these brief descriptions of some of the limitations of directors and gun sights, it will be apparent that the usefulness of the former de-

2

creases as the range is reduced, and the usefulness of the latter decreases as the range is increased. Therefore, it may be desirable to have a director for aiming certain intermediate range guns more accurately than a gun sight, and yet be less complex and capable of predicting future positions more rapidly than the aforementioned directors.

Since shorter range guns can only protect a very limited area, it follows that more guns will be required than in the case of long range guns. For this reason, a less complex director is desirable in order to permit the manufacture of more units with a given amount of time and materials.

15 This intermediate range may be said to lie between 500 yards and 5000 yards slant range, that is, the range in which the linear distance of the target from the gun is between 500 and 5000 yards. These distances are merely illustrative of 20 an intermediate range, and are not intended as limiting the invention.

In the solution of fire control problems, the velocity and direction of flight of the target may be represented vectorially by a system of three 25 mutually perpendicular vectors representing component velocities of the target. By multiplying each of these component velocities by the time of flight of a projectile from the gun to the predicted future position of the target, we may obtain vectors representing three components of 30 the movement of the target from its present position to its future position. Then, by adding the three vectors representing the product of velocity times time of flight, we may determine the future 35 position of the target.

It will be apparent that the time of flight is dependent upon the future position of the target. Hence the exact time of flight may only be ascertained by a series of approximations in which a

40 time of flight is calculated on the basis of a known position and the future position estimated for this time of flight; time of flight to this future position again calculated and a later future position determined, etc. Considerable time is required 45 for the computing mechanism to make this series of approximations. However, an accurate time of flight is of value where accurate predictions are desired, as, for example, when long range guns are used.

50 It will be apparent that the time of flight is a function of the linear distance from the gun to the future position of the target and the elevation of the future position of the target with respect to the plane of the gun. It is, of course, 55 also necessary for this time of flight to be cor-

rected in accordance with the ballistics of the particular projectile used.

The effect of the elevation of the target upon the time of flight is small. For short and intermediate ranges, the factor of future elevation may be eliminated from computations of the time of flight. Furthermore, the linear distance from the gun to the future position of the target is, for intermediate and short ranges, approximately equal to the algebraic sum of the linear distance from the gun to the present position of the target and the product of the rate of change of this distance multiplied by the time of flight. From this, it may be said that the time of flight is a function of the linear distance and the rate of change of that distance.

In the present invention, a fictitious time of flight, hereinafter called the corrected time of flight (t'_p) is used to obtain prediction. This corrected time of flight is a value based on an approximate function of present slant range and slant range rate which may be multiplied by angular rates to obtain accurate prediction.

One expression for the corrected time of flight (t'_p) is,

$$t'_p = \frac{D_o t_p}{D_o + \dot{D} t_p}$$

wherein D_o is the linear distance from the gun to the target and $\dot{D}$ is the rate of change of that distance and t_p is the time of flight of a projectile from the gun to the future position of the target. This equation is intended solely as an example of one calculation of the corrected time of flight. the value t'_p however will be used throughout the specification to designate a corrected time of flight that will give an accurate computation of the prediction angle when multiplied by the angular rate of the target.

From the foregoing, it may be said that the corrected time of flight is a function of slant range (D_o) and slant range rate ($\dot{D}$). Various functions of D_o and $\dot{D}$ may be used to obtain a desired corrected time of flight, as will herein-after appear.

One of the objects of the present invention is to provide a relatively simple director for accurately controlling the fire of guns for intermediate ranges.

Another object of the invention is to provide a director for aiming guns that will rapidly predict the future position of the target.

A further object of the invention is to provide a prediction mechanism which will compute a time of flight immediately from data supplied to the mechanism.

A further object of the invention is to provide a prediction mechanism in which a corrected time of flight is computed from the linear distance between the gun and the present position of the target and the rate of change of that distance.

A still further object of the invention is to provide a prediction mechanism for intermediate range directors which will accurately compute the future position of a target from information supplied as to the rates of change of the elevation and azimuth positions of the target and a corrected time of flight.

Other objects and advantages of the invention will become apparent from the following description taken in connection with the accompanying drawings which show specific embodiments of the invention wherein:

Fig. 1 is a space diagram showing the vector

relationships used in the solution of the prediction problem.

Fig. 2 is a schematic diagram of a director embodying the invention in one form, and

Fig. 3 is a schematic diagram of a director embodying the invention in another form.

Fig. 3A is a schematic drawing of a director.

In order to facilitate an understanding of Fig. 1 the following are definitions of the various angular, linear and vector designations used in the present solution of the prediction problem.

T_o is the observed or present position of the target.

T_p is the predicted future position of the target. t_p is the time of flight of a shell or a projectile from the gun to the future position of the target.

t'_p is a corrected time of flight based on an approximate function of present slant range and slant range rate.

A'_o is the observed or present azimuth of the target relative to a point in the horizontal plane of the gun.

A_p is the predicted future azimuth of the target relative to the same point in the horizontal plane of the gun.

E_o is the observed or present elevation of the target relative to the horizontal plane of the gun.

E_p is the predicted future elevation of the target relative to the horizontal plane of the gun.

R_o is the observed or present horizontal range of the target, that is, the linear distance from the gun to a projection of T_o on the horizontal plane.

R_p is the future horizontal range of the target, that is, the linear distance of the gun to the projection of T_p on the horizontal plane.

H_o is the observed or present altitude of the target above the horizontal plane of the gun.

H_p is the predicted future altitude of the target relative to the horizontal plane of the gun.

D_o is the observed or present slant range of the target, that is, the linear distance between the target and the gun.

D_p is the future predicted slant range of the target, that is, linear distance between the future position T_p of the target and the gun.

The "horizontal plane" is a horizontal plane including the gun.

The vertical plane is a plane perpendicular to the horizontal plane and including the present position of the target and the gun.

The slant plane is a plane perpendicular to the vertical plane and including the gun and the present position of the target.

δ is the prediction angle, that is, the angle between a line including the gun and the present position of the target and a line including the gun and the future position of the target.

δE_s is the elevation component of the prediction angle measured in the vertical plane.

δA_s is the azimuth component of the prediction angle measured in the slant plane.

ΔA is change in the azimuth angle measured in the horizontal plane.

ΣA_s is the azimuth angular velocity of the target measured by a tracking device in the slant plane.

ΣA_H is the azimuth angular velocity of the target measured by a tracking device in the horizontal plane.

ΣE is the elevation angular velocity of the target measured by a tracking device in the vertical plane.

In Fig. 1 the point O represents a position of the gun; the plane OAB is the vertical plane through the gun; OBC is the horizontal plane perpendicular to the vertical plane and ODE is the slant plane through the gun and perpendicular to the vertical plane at OD defined by the line of sight.

The target when in position T_o has a certain velocity (V) toward the future position T_p .

By multiplying the velocity (V) by the time of flight (t_p) the distance between T_o and T_p is obtained. This distance is referred to as prediction.

The velocity V may be resolved into three components, one along the line of sight or slant range designated as the slant range rate; one in the slant plane designated as the slant plane azimuth rate; and one in the vertical plane designated as the elevation rate. It will be apparent that these three component velocities are mutually perpendicular and may be added vectorially to determine the resultant velocity V.

Likewise, each of the components of the velocity may be multiplied by the time of flight to obtain three components of the prediction, one along the line of sight, one in the slant plane, and one in the vertical plane. These three components are represented by vectors in Fig. 1. The range component is designated $\dot{D}t_p$; the slant plane component is designated $\Sigma_{AS}D_o t_p$ and the vertical plane component is designated $\Sigma_E D_o t_p$.

Information containing the range rate ($\dot{D}$) is supplied by a range finder in the form of continuous slant range and the range prediction component ($\dot{D}t_p$) may be readily calculated. However, it is not possible to measure the linear velocities of the target in the slant and vertical planes. In order to obtain value for the vectors, in Fig. 3, the azimuth angular velocity in the slant plane (Σ_{AS}), and the elevation velocity in the vertical plane (Σ_E) are measured. The computer of Fig. 2 measures the azimuth velocity in a horizontal plane (Σ_{AH}).

If these angular velocities are multiplied by the distance (D_o) that the target is from the gun, two linear component velocities of the target ($\Sigma_{AS}D_o$, $\Sigma_E D_o$) are obtained which are at right angles to each other and to the radius vector, D_o , and the component velocity ($\dot{D}$).

If the component velocities are multiplied by the time of flight, the following linear predictions ($\Sigma_{AS}D_o t_p$, $\Sigma_E D_o t_p$, $\dot{D}t_p$) are obtained. The vector addition of these give the change of position of the target. From the foregoing, it will be apparent that the three mutually perpendicular vectors representing the components of the target's movement from the present position T_o to the future position (T_p) are designated by $\Sigma_E D_o t_p$ for the elevation component in the vertical plane; $\Sigma_{AS}D_o t_p$ for the azimuth component in the slant plane; and $\dot{D}t_p$ for the range component. From these vectors, the azimuth and elevation prediction angles can be obtained. In the embodiment of the invention shown in Fig. 3 the azimuth component is computed in a slant plane as just described and is then transformed into a horizontal plane for furnishing data for controlling the position of a gun in azimuth. In Fig. 2 the angular velocity Σ_{AH} of the target is measured directly in a horizontal plane and multiplied there by time of flight. Transformation of the azimuth data from slant plane to horizontal plane is not required in this case and the diagram

of Fig. 1 only applies generally to the embodiment of Fig. 2.

The following equations, some of which are approximations, are thought to be sufficient to give an understanding of the mechanism about to be described. The equations are believed to be in such form as to give those skilled in the art an understanding of the invention and therefore details of their derivation have been omitted.

10 Referring to Fig. 1, it may be shown that

$$\tan \delta E_s = \frac{\Sigma_E D_o t_p}{D_o + \dot{D}t_p} \quad (1)$$

15 As previously explained the corrected time of flight (t'_p) may be computed as a function of D_o and $\dot{D}$ in accordance with the following equation:

$$t'_p = \frac{D_o t_p}{D_o + \dot{D}t_p} \quad (2)$$

20 Hence, by substituting t'_p in Equation 1

$$\tan \delta E_s = \Sigma_E t'_p \quad (3)$$

From Fig. 1 it will also be apparent that

$$25 \tan \Delta A = \frac{\Sigma_{AS} D_o t_p}{R_o + \dot{R}t_p} \quad (4)$$

and

$$R_o + \dot{R}t_p = C \cos (E_o + \delta E_s) = \\ (D_o + \dot{D}t_p) \sec \delta E_s \cos (E_o + \delta E_s) \quad (5)$$

30 hence,

$$\tan \Delta A = \frac{\Sigma_{AS} D_o t_p}{(D_o + \dot{D}t_p) \sec \delta E_s \cos (E_o + \delta E_s)} \quad (6)$$

35 By substituting Equation 2 in Equation 6

$$\tan \Delta A = \frac{\Sigma_{AS} t'_p}{\sec \delta E_s \cos (E_o + \delta E_s)} \quad (7)$$

This may be written as

$$40 \tan \Delta A = \frac{\Sigma_{AS} t'_p}{(1 - \tan E_o \tan \delta E_s) \cos E_o} \quad (8)$$

and since

$$\frac{R_o}{D_o} = \frac{\Sigma_{AH}}{\Sigma_{AS}} = \cos E_o \quad (9)$$

45 By substituting for Σ_{AS} in Equation 8

$$\tan \Delta A (1 - \tan E_o \tan \delta E_s) = \Sigma_{AH} t'_p \quad (10)$$

From Fig. 1 it may also be shown that

$$50 H_p = R_p \tan E_p \quad (11)$$

and that

$$H_p = (R_o + \dot{R}t_p) \tan (E_o + \delta E_s) \quad (12)$$

55 hence, by equating the values of H_p in Equations 11 and 12

$$R_p \tan E_p = (R_o + \dot{R}t_p) \tan (E_o + \delta E_s) \quad (13)$$

Since from Fig. 1

$$60 R_o + \dot{R}t_p = R_p \cos \Delta A \quad (14)$$

By substituting the value of $R_o + \dot{R}t_p$ in Equation 13

$$65 R_p \tan E_p = R_p \tan (E_o + \delta E_s) \cos \Delta A \quad (15)$$

This may be written as

$$E_p = \tan^{-1}(\tan (E_o + \delta E_s) \cos \Delta A) \quad (16)$$

70 For a reason to be subsequently explained, the sum of E_o and δE_s is subtracted from both sides of Equation 16 to give

$$\Delta E = \tan^{-1}(\tan (E_o + \delta E_s) \cos \Delta A) - (E_o + \delta E_s) \quad (17)$$

75 By the mechanism shown in Fig. 2 it is pro-

posed to solve Equations 2, 3, 10 and 17 to obtain values of t'_p , δE_s , ΔA , and ΔE . When these values are available, an accurate prediction of the future position of the target may be computed.

From a suitable range finding mechanism which may be of either the optical or radio type, a value of the present range (D_o) of the target is continuously supplied to the operator of the director. The director operator introduces this value of present range continuously into the director by means of a handwheel 1 on a shaft 2 which carries a pinion 3 which meshes with a rack 4 to displace ball carriage 5 of a variable speed drive mechanism designated generally at 6. A disc 7 of the variable speed drive 6 is driven by a constant speed motor 8. It will be apparent that cylinder or drum 9 of the variable speed drive will be rotated at a speed proportional to the displacement of the ball carriage.

If the operator is supplied with the value of present slant range on a dial, he will turn the handwheel 1 until the ball carriage 5 is displaced sufficiently to rotate the drum 9 at a speed whereby a range indicator 10 will be matched with the value appearing upon the range indicator (not shown) that is positioned by the range finder mechanism. When the indications are matched, the ball carriage and therefore the shaft 2 both will be displaced an amount proportional to the rate of change in the slant range. A pinion 12 on the shaft 2 meshes with a rack 13 that translates a three-dimensional cam designated generally at 14 in accordance with the rate of change in slant range (D).

The drum 9 drives one input of a differential 15; the other input is driven by the shaft 2. The output shaft 16 is thereby rotated an amount proportional to a present slant range (D_o) of the target at any given instant. This shaft carries an elongated pinion 17 that drives a gear 18 to rotate the cam 14. One surface 19 of the cam 14 is laid out in accordance with Equation 2 as a function of the slant range and the slant range rate. Since the cam is translated in accordance with the slant range rate and rotated by an amount proportional to the slant range, movements of a follower 21 that rides on the surface 19 will be proportional to the corrected time of flight (t'_p).

Follower 21 is provided with a rack 22 that meshes with a pinion 23 to turn a shaft 24 an amount proportional to the corrected time of flight (t'_p). The rotation of this shaft displaces a ball carriage 25 of a variable speed drive mechanism designated generally by 26 by means of a rack 27 connected to the ball carriage 25 and a pinion 28 on the shaft 24. Similarly the ball carriage 29 of a variable speed drive designated generally at 31, is displaced by rotation of a pinion 32 on the shaft 24 that meshes with a rack 33 which is connected to the ball carriage.

An operator may track the target in elevation by any suitable means, such as telescope 34 that is rotated about a horizontal axis. The operator keeps the reticle of this telescope 34 on the target by adjusting a handwheel 35 which turns a shaft 36 which carries a pinion 37 meshing with a rack 38 that displaces a ball carriage 39 of a variable speed drive mechanism designated generally at 41 in accordance with the rotation of the shaft 36. Displacement of the ball carriage 39 transmits motion from a

disc 42 that is driven by constant speed motor 43 to a drum 44 that is thereby rotated at a speed proportional to the extent of rotation of the shaft 36. One input of a differential 45 is driven by the shaft 36 and another input 46 is driven by the drum 44.

It will be apparent that the output 46 of the differential 45 will rotate at a speed proportional to the elevation angular velocity of the target in a vertical plane (ΣE) provided of course the telescope 34 is maintained on the target. Telescope 34 is rotated about a horizontal axis at a speed proportional to the speed of shaft 46 by means of a pinion 47 that drives a gear 48 connected to the telescope 34 by a shaft 49.

The shaft 46 in addition to being rotated at a speed proportional to the elevation angular velocity (ΣE) of the target is also rotated by an amount proportional to the present elevation (E_o) of the target. A shaft 51 driven by the shaft 46 through bevel gears 52 and 53, rotates through bevel gears 54 and 55 shaft 56 at the same speed as shaft 46. This shaft 56 drives a disc 57 of the variable speed drive 26.

Since the ball carriage 25 of the variable speed drive 26 is displaced an amount proportional to the corrected time of flight t'_p , and the disc 57 is rotated at a speed proportional to the elevation velocity ΣE of the target, the drum 58 will be rotated at a speed proportional to the product of ΣE and t'_p .

Drum 58 drives a shaft 59 that is connected to one of the inputs of an equating device 61 which may be of any suitable mechanical or electrical form such as a differential, an eddy current device, or a transformer for supplying zero output when the two input rates are matched. The other input, shaft 62 of the device 61, is driven by a drum 63 of a variable speed drive designated generally at 64. A disc 65 of this variable speed drive is rotated by a constant speed motor 66.

The device 61 operates follow-up contacts 67 and 68 to energize a follow-up motor 69 which then rotates in one direction or another depending upon which of the input shafts of the device 61 is rotating at a greater speed. When the input shafts are rotating at equal speeds, both of the contacts 67 and 68 are open.

The follow-up motor 69, hereinafter referred to as the δE_s follow-up motor, drives a cylinder 71 having a cam groove 72 which moves a follower 73 an amount proportional to the tangent function of the movements of the δE_s follow-up motor. The follower 73 displaces a ball carriage 74 of variable speed drive 64. Since the disc 65 is rotated at a constant speed, the drum 63 will be rotated at a speed proportional to $\tan \delta E_s$, provided of course the δE_s follow-up motor is rotated an amount proportional to the elevation component of the prediction angle (δE_s).

In operation, drum 58 of the variable speed drive 26 will be rotated at a speed proportional to the product of the elevation velocity of the target (ΣE) and the corrected time of flight (t'_p). This rotation will cause the device 61 to close one of the contacts 67 or 68 to drive follow-up motor 69 an amount sufficient to displace ball carriage 74 so drum 63 will be rotated at the same speed as drum 58. When equilibrium is reached, it will be apparent that the conditions of Equation 3 have been fulfilled and the follow-up motor will necessarily have rotated an amount proportional to the elevation component of the prediction angle (δE_s).

The follow-up motor 69 is coupled to a shaft 75 which drives one of the inputs to differential 76 referred to further on and also rotates a pinion 77 that meshes with a rack 78 to translate a cam 79. The shaft 46 operates through bevel gears 81 and 82 to drive a shaft 83 which carries an elongated pinion 84. The pinion 84 meshes with a gear 85 to rotate the cam 79.

The cam 79 is translated an amount proportional to the elevation component of the prediction angle (δE_s) and rotated in an amount proportional to the present elevation angle (E_o). The surface of the cam 79 is laid out in a manner such that follower 86 will be displaced by the cam 79 an amount proportional to $(1 - \tan E_o \tan \delta E_s)$. Follower 86 displaces a ball carriage 87 of a variable speed drive designated generally at 88 having a disc 89 which is driven by the constant speed motor 66. Thus drum 91 of the variable speed drive 88 is rotated at a speed proportional to the expression $(1 - \tan E_o \tan \delta E_s)$.

A drum 91 drives shaft 92 which also rotates a disc 93 of a variable speed drive designated generally at 94 in accordance with the expression $(1 - \tan E_o \tan \delta E_s)$.

The azimuth operator rotates a handwheel 95 to track the target in azimuth by means of a telescope 96 in a manner similar to that described in connection with the elevation operator. Rotation of the handwheel 95 turns the shaft 97 carrying a pinion 98 which meshes with a rack 99 that is connected with ball carriage 101 of a variable speed drive designated generally at 102. The variable speed drive has a disc 103 driven by a constant speed motor 104. Rotation of handwheel 95 causes displacement of the ball carriage 101 whereby drum 105 is rotated at a speed proportional to the azimuth velocity (ΣA_H) of the target measured in the horizontal plane, since the telescope 96 is rotated about a vertical axis.

The telescope 96 is rotated to follow the target by a shaft 106 that is rotated by gear 107 which is driven by a pinion 108. Rotation of cylinder 105 rotates a shaft 109 which drives one of the inputs of a differential 111 the other input of which is driven by the shaft 97. It will be apparent that the output shaft 112 of the differential 111 is rotated an amount proportional to the present azimuth angle (A_o) of the target and is rotated at a speed proportional to the azimuth velocity (ΣA_H) of the target in the horizontal plane.

Shaft 112 acts through bevel gears 113 and 114 to drive a shaft 115 that rotates disc 116 of the variable speed drive 31. Since the ball carriage 29 of the variable speed drive 31 is displaced an amount proportional to the corrected time of flight (t'_p), drum 117 of the variable speed drive will be rotated at a speed proportional to the product of the azimuth velocity of the target in a horizontal plane and the corrected time of flight ($\Sigma A_H \times t'_p$).

The drum 117 drives a shaft 118 which forms one of the inputs of an equating device 119 similar to the device 61 previously described. The device 119 controls electrical contacts 121 and 122 whereby a follow-up motor 123 is energized to rotate in one direction or another depending upon which of the input shafts of the device 119 is rotating at a greater speed. The motor 123, hereinafter referred to as the ΔA follow-up motor, rotates a shaft 124 which drives a shaft 125 through bevel gears 126 and 127.

Shaft 125 rotates a cylinder 128 having a cam

75

groove 129 that positions a follower 130 in accordance with the tangent function of the rotation of the shaft 125, that is $\tan \Delta A$. Follower 130 displaces a ball carriage 131 of the variable speed drive 94. Since the disc 93 of the variable speed drive 94 is rotated at a speed proportional to the expression $(1 - \tan E_o \tan \delta E_s)$ and the ball carriage is displaced an amount proportional to $\tan \Delta A$, drum 132 of the variable speed drive is rotated at a speed proportional to the product $\tan \Delta A (1 - \tan E_o \tan \delta E_s)$.

When equilibrium is reached and both contacts 121 and 122 of the device 119 are open, the follow-up motor will have rotated shaft 124 an amount proportional to the change in the azimuth angle (ΔA) and the Equation 10 will be satisfied.

The ΔA follow-up motor 123 rotates shaft 133 which drives one of the inputs to a differential 134, an amount proportional to the angle (ΔA). The other input of the differential 134 is driven by a shaft 135 that is driven through bevel gears 136 and 137 by shaft 112 an amount proportional to the present azimuth (A_o) of the target. Therefore, the differential 134 rotates a shaft 138 an amount proportional to the algebraic sum of the present azimuth angle (A_o) and the change in azimuth angle (ΔA). Since this sum is equal to the future azimuth angle or angle of train of the guns, the shaft 138 may position a suitable data transmitter 139. This transmitter may be of any suitable type such as a "Selsyn" or "Telegon" that transmits the angle of train data to the guns in a conventional manner.

Rotation of shaft 124 rotates a pinion 141. This pinion meshes with a rack 142 which translates a cam 143 in accordance with the change in azimuth angle (ΔA). Cam 143 is rotated by a gear 144 driven by an elongated pinion 145 that is rotated by a shaft 146. Shaft 146 is driven by the output of the differential 76, the inputs of which are driven by shafts 75 and 83. Since the rotation of these two shafts is proportional to the elevation component of the prediction angle (δE_s) and the present elevation angle (E_o), respectively, the output of the differential 76 will drive shaft 146 an amount proportional to the algebraic sum of these two angles. Hence, the cam 143 will be rotated an amount proportional to the sum of these two angles.

Since the cam 143 is translated proportionally to ΔA and rotated an amount proportional to $(E_o + \delta E_s)$, the cam surface might be designed to move a cam follower an amount proportional to E_p in accordance with Equation 16. However, this would be a very large angle and would require the use of poor scale factors. Since the cam 143 is rotated in accordance with the sum of the angles (E_o) and (δE_s), this sum may be subtracted from the surface of the cam thus providing the movement of a cam follower over the surface of a cam an amount proportional to $E_p - (E_o + \delta E_s)$. This value is designated ΔE and the cam 143 is laid out in accordance with Equation 17.

Thus, cam follower 147 is displaced an amount proportional to ΔE . A rack 148 connected to the cam follower 147 rotates a pinion 149 which drives a shaft 151 forming one of the inputs to a differential 152. The other input of the differential 152 is driven by the shaft 146 which is rotated an amount proportional to the sum of the angles (E_o) and (δE_s). Shaft 153 representing the output of differential 152 will thus be rotated an amount proportional to $E_o + \delta E_s + \Delta E$ or an amount proportional to the future elevation angle (E_p). This future elevation angle is the actual

75

elevation of the future position of the target. In order to supply elevation data to the guns it is necessary to correct the elevation prediction angle for variations due to the trajectory of the projectile in the vertical plane, that is, super-elevation (ϕ).

For purposes of this director, it has been assumed that super-elevation (ϕ) is a function of future slant range (D_p), and the angle equal to the sum of the present elevation angle and the elevation component of the prediction angle, namely, ($E_o + \delta E_s$).

As was stated at the outset of the present description, future slant range (D_p), when prediction angles are small, is approximately equal to the sum of the present slant range (D_o) plus the product of the slant range rate (D) times the time of flight (t_p). Since the time of flight (t_p) is a function of the slant range (D_o) and slant range rate (D), the future range (D_p) may be said to be approximately equal to a function of the present slant range (D_o) and slant range rate (D). Based on this information, another surface 154 of the cam 14 may be laid out to displace a follower 155 an amount approximately equal to the future slant range (D_p) for given values of the present slant range (D_o) and range rate (D) which translate and rotate the cam 14 respectively.

Follower 155 displaces a super-elevation (ϕ) cam 156. The cam 156 is rotated by a gear 157 that is driven by a pinion 158. Pinion 158 is rotated an amount proportional to ($E_o + \delta E_s$) by gearing from the shaft 146 including pinion 159, gear 161, bevel gears 162 and bevel gears 163 which drive a shaft 164 on which the pinion 158 is mounted. It will be apparent that the lift of follower 165 on cam 156 will be proportional to the super-elevation, since the surface of the cam is designed to give this value for given values of future range (D_p), and ($E_o + \delta E_s$) which translate and rotate the cam 156, respectively.

Follower 165 translates a rack 166 which engages and rotates a pinion 167 to drive one of the inputs of a differential 168 by means of a shaft 169. The other input of the differential 168 is driven by the shaft 153 in accordance with the future elevation angle (E_p). Thus, this differential 168 algebraically adds the future elevation (E_p) and the super-elevation (ϕ) to drive from its output a shaft 171 in accordance with the quadrant elevation to be transmitted to the guns. The shaft 171 positions a quadrant elevation transmitter 172 that may be of any well known type such as a "Selsyn" or "Telagon" transmitter that is adaptable to transmit elevation data to the guns.

For comparatively small prediction angles the director described will give very accurate results although the mechanism is much less complex than the directors used for longer ranges. Also, the prediction mechanism gives an accurate solution within a very short time after the operators begin tracking a target.

Although simplicity has been stressed in the above description of the intermediate range director, the advantageous arrangement of the various mechanisms should also be noted. For example, very little force is required of the respective cam followers. With the exception of the ΔE cam follower, these followers are used only to displace ball carriages of variable speed drive or to displace other cams. The ΔE cam follower is used only to drive one input of the

differential 152. Those devices in the director requiring larger torques are driven either by variable speed drives or by motors.

In Fig. 3 another intermediate range director embodying the invention is shown. The prediction solution obtained by this mechanism is similar to that described in connection with the director shown in Fig. 2.

Referring again to Fig. 1, the prediction solution in the present mechanism uses the same vector components of the movement of the target from its present position (T_o) to its future position (T_p). From Fig. 1 it will be seen that

$$\delta E_s = \tan^{-1} \frac{\Sigma E D_o t_p}{D_o + \dot{D} t_p} \quad (1)$$

and

$$\delta A_s = \tan^{-1} \frac{\Sigma A S D_o t_p}{D_o + \dot{D} t_p} \quad (2)$$

As was previously pointed out, a corrected time of flight of a projectile from the gun to the future position of the target may be computed on the basis of the following equation

$$t'_p = \frac{D_o t_p}{D_o + \dot{D} t_p} \quad (3)$$

By substituting the value of t'_p in Equations 1 and 2, it will be seen that

$$\delta E_s = \tan^{-1} \Sigma E t' p \quad (4)$$

and

$$\delta A_s = \tan^{-1} \Sigma A S t' p \quad (5)$$

Thus, the elevation component (δE_s) of the prediction angle may be determined from the elevation velocity (ΣE) of the target and the corrected time of flight, which is a function of the present range (D_o) and the range rate ($\dot{D}$).

If we have the values of the slant range (D_o), slant range rate ($\dot{D}$), elevation velocity (ΣE) and azimuth velocity ($\Sigma A S$) in the slant plane, it is possible to compute the elevation component (δE_s) and azimuth or lateral component (δA_s) in the slant plane of the total prediction angle, that is the angle between the present slant range of the target and the future slant range (D_p). Having obtained these components in the slant plane, it is only necessary to convert them to the horizontal plane in order to obtain the future elevation (E_p) of the target and the future azimuth (A_p). The future azimuth (A_p) is merely the sum of the present azimuth (A_o) and the change in azimuth (ΔA).

The director illustrated in Fig. 3 is supplied with present slant range information continuously from a suitable range finder (not shown) in a manner similar to that described in connection with Fig. 2. This information may be supplied in any conventional manner, as, for example, by a range indicator. The operator of the director introduces this slant range (D_o) continuously into the director by matching a range indicator 181 with the range indicator that is actuated by the range finder.

The range operator matches the indicator 181 by adjusting a handwheel 182 that rotates shaft 183 carrying a pinion 184. The pinion 184 meshes with a rack 185 to translate ball carriage 186 of a variable speed drive, designated generally as 187, the disc 188 of which is driven by a constant speed motor 189. When the indicator 181 is continuously matched with the indicator actuated by the range finder, the ball carriage 186 will be displaced an amount proportional to the rate of change of the slant range, and the cyl-

inder 191 of the variable speed drive 187 will be rotated at a speed proportional to this slant range rate (D). The cylinder 191 rotates a shaft 192 which drives one input of a differential 193, the other input being driven by a shaft 194 that is rotated through bevel gears 195 and 196 by the shaft 183. The output of this differential is equal to the present slant range (D_o) of the target, and the shaft 163 is rotated an amount proportional to the rate of change (D) of this range.

A lead screw 197 on the shaft 183 translates a support 198 for a pair of cams 199 and 201 that are rotatably mounted in the support 198. These cams have gears 202 and 203 that mesh with pinions 204 and 205, respectively, on a shaft 206 that is rotated by the output of the differential 193 in accordance with present range of the target. It will be apparent, therefore, that the cams 199 and 201 are translated an amount proportional to the slant range rate (D) of the target and are rotated an amount proportional to the slant range (D_o) thereof.

The surface of the cam 199 is laid out in such a manner that the lift of a follower 207 riding thereon will be proportional to the corrected time of flight which, as has been previously explained, is approximately equal to a function of the slant range and slant range rate.

The follower 207 translates a pair of cams 208 and 209 which are rotated in accordance with the azimuth slant plane and elevation velocities, respectively, of the target in a manner to be described.

A free gyro designated generally at 211 is rigidly mounted on the sighting instrument (not shown) of the director which tracks the target in elevation and azimuth. One arrangement for providing azimuth and elevation movements for the sighting instrument is to mount the director casing for rotation in azimuth on a pedestal and to mount the sighting instrument on the director casing for rotation about a horizontal axis (in elevation) relative to the casing. The gyro 211 is of conventional construction, having a rotor 212 pivotally mounted in a gimbal ring 213 which is supported in frame 214 so it is free to rotate about a horizontal axis. A shaft 215 integral with the rotor of the gyro 211 is restrained against movement about a vertical axis by a ring indicated schematically as a bail 216 for controlling movements of the gyro about this vertical axis.

In tracking the target, the operator controls movements of the sight by applying torques to the gyro through rotation of handwheels 217 and 218 for slant azimuth and elevation, respectively. Rotation of the handwheel 217 acts through shaft 219, bevel gears 221 and 222 and compensating differential 220 to rotate shaft 223. This shaft drives through bevel gears 224 and 225 to rotate shaft 226 which applies torque to the horizontal shaft 227 of the gyro by means of a pulley 228, springs 229 and pulley 230 on the shaft 227.

Torque applied to the shaft 227 is applied to the horizontal axis of the gyro, and will cause the gyro rotor to precess about its vertical axis at a rate proportional to the torque applied. This movement of the gyro rotor about its vertical axis causes the shaft 215 to move the ring 216, thus displacing arm 231 attached thereto. The arm 231 is arranged alternatively above a pair of contacts 232 and 233, depending upon the direction in which the gyro precesses. As will subsequently appear, these contacts 232 and 233 control an azimuth motor which drives the director casing,

sight and gyro frame 214 in azimuth at a rate determined by the precession of the gyro rotor.

Similarly, rotation of handwheel 218 applies torque to the vertical axis of the gyro through shaft 234, bevel gears 235 and 236, compensating differential 240, shaft 237, pulleys 238 and 239 and springs 241. This torque applied to the vertical axis of the gyro causes the gyro rotor to precess about its horizontal axis at a rate proportional to the torque applied. This precession about this horizontal axis causes arm 243 to close one of the contacts 244 or 245, depending upon the direction of the movement of the gyro.

Contacts 244 and 245 control the direction of rotation of a motor 246 which rotates the sight and gyro frame 214 in elevation relative to the director casing by means of mechanism shown schematically in Fig. 3A of the drawings. The rate of this rotation in elevation is proportional to the elevation precession rate of the gyro, and hence is proportional to the torque applied by rotation of handwheel 218.

In tracking a target in elevation, the sighting instrument and gyro must move relative to the casing. Assuming a certain torque is applied through handwheel 218, the gyro rotor will precess in about its horizontal axis at a rate proportional to the torque applied. This precession causes motor 246 to move the gyro frame together with the sight relative to the director casing. Provision must be made to prevent the application of undesired torque due to this relative movement. Shafts 401 and 402, forming inputs to differentials 220 and 240, are rotated by shaft 403 from motor 246 through suitable gearing 404 and 405 in accordance with the elevation movement (E_o) of the gyro frame 214 and the sighting instrument. Thus, the outputs of differentials 220 and 240, namely shafts 223 and 237 rotate with the gyro frame in elevation, and rotate relative to the gyro frame only to apply torque proportional to the displacement at handwheels 217 and 218.

The tracking operator, by turning the handwheels 217 and 218, causes the gyro to precess about its vertical and horizontal axes at a rate proportional to the slant azimuth and elevation velocities of the target in order to keep the sighting instrument tracking the target.

From the foregoing description, it will be seen that the angular displacement of the shaft 219 by handwheel 217 is proportional to the azimuth angular rate of the target in a slant plane (Σ_{AS}), provided the sight is tracking the target. Rotation of the shaft 219 acts through bevel gears 251 and 252 to drive a shaft 253. Shaft 253 rotates an elongated pinion 254, which meshes with a gear 255 on the cam 208 to rotate the cam an amount proportional to the slant azimuth velocity of the target in the slant plane (Σ_{AS}). Since the cam 208 is translated by the follower 207 in accordance with the corrected time of flight (t'_p), and rotated in accordance with the slant azimuth velocity (Σ_{AS}), it is so laid out that the lift of follower 255 riding thereon will be proportional to δ_{AS} in accordance with Equation 5.

Rotation of shaft 234 by handwheel 218 rotates the cam 209 in accordance with the elevation rate (Σ_E) by driving through bevel gears 257 and 258 to rotate an elongated pinion 259 that meshes with a gear 261 on the cam 209. Cam 209 is so laid out that the lift of a follower 262 riding thereon will be proportional to the elevation component (δE_s) of the total prediction angle in accordance with Equation 4.

Having thus obtained the elevation and azimuth components (δE_s) and (δA_s) in the slant plane, it is only necessary to convert these component angles to the horizontal plane in order to compute the future position of the target. In order to accomplish this, conversion cams are translated and rotated in accordance with the elevation and azimuth components of the prediction angle and the present elevation (E_o) to obtain the change in azimuth (ΔA) and future elevation (E_p) in accordance with the following equations

$$\Delta A = \tan^{-1} \left(\frac{\tan \delta A_s \cos \delta E_s}{\cos (E_o + \delta E_s)} \right) \quad (6)$$

$$E_p = \sin^{-1} \left(\frac{\sin (E_o + \delta E_s)}{\sqrt{1 + \tan^2 \delta A_s \cos^2 \delta E_s}} \right) \quad (7)$$

The mechanism shown in Fig. 3 for translating and rotating the conversion cams to solve the above equations will now be described.

A rack 263 on the follower 262 meshes with a pinion 264 to rotate a shaft 266 an amount proportional to the elevation component (δE_s) of the prediction angle. This shaft 266 forms one input of an equating device 267, such as a differential, that actuates a pair of contacts 268 and 269 to control the direction of rotation of a follow-up motor 270. A shaft 271, that is driven by the motor 270 through bevel gears 272 and 273, forms the other input of the equating device. It will be apparent that rotation of the shaft 266 will cause the equating device 267 to close contacts 268 and 269 until the motor 270 drives the shaft 271 an amount proportional to the elevation component (δE_s) of the prediction angle.

The shaft 271 carries a lead screw 277 which, upon rotation of the shaft 271, translates a support 278. A pair of cams 279 and 281 are rotatably mounted in the support 278.

The lift of the follower 256 rotates a pinion 282 by means of rack 283 to drive one input of an equating device 284 in accordance with the azimuth component (δA_s) of the prediction angle in the slant plane. The device 284 controls follow-up contacts 285 and 286 which energize a follow-up motor 287 to drive a shaft 291 through bevel gears 288 and 289. The shaft 291 drives the other input of the equating device 284 and is thus rotated an amount proportional to the slant azimuth component (δA_s) of the prediction angle.

Rotation of shaft 291 acts through elongated pinions 293 and 294 which mesh with gears 295 and 296, respectively, to rotate the cams 279 and 281 amounts proportional to the slant azimuth component (δA_s) of the total prediction angle.

As will be seen, the cam 279 is translated in accordance with the elevation component (δE_s) of the prediction angle and is rotated in accordance with the slant azimuth component (δA_s) of the prediction angle. The surface of the cam 279 is such that the lift of a follower 301 riding thereon will be proportional to the expression ($\tan \delta A_s \cos \delta E_s$).

The lift of the follower 301 translates a cam 302 which is rotated in accordance with the sum of the present elevation angle (E_o) and the elevation component (δE_s) of the prediction angle, that is, the expression ($E_o + \delta E_s$). Rotation of the cam 302 in accordance with the sum of these two angles is accomplished in the following manner.

The shaft 271, which is rotated an amount proportional to the elevation component (δE_s) of the

prediction angle, drives through bevel gears 303 and 304 to rotate a shaft 305. The shaft 305 then drives gears 306 and 307 to rotate a shaft 308 an amount proportional to δE_s . The shaft 308 drives one input of a differential 309, the other input of which is driven by a shaft 311 that is rotated by the motor 246. As was explained above, the elevation follow-up motor 246 is driven in a direction to rotate the sighting instrument which follows the gyro in elevation. This motor is also used to drive present elevation (E_o) into the director by rotating shaft 311.

The output of differential 309 rotates a shaft 312 an amount proportional to the sum ($E_o + \delta E_s$). This shaft acts through elongated pinion 313 which meshes with gear 314 to rotate the cam 302 in accordance with the expression ($E_o + \delta E_s$).

Since the cam 302 is translated in accordance with the expression ($\tan \delta A_s \cos \delta E_s$) and is rotated in accordance with the sum ($E_o + \delta E_s$), the surface of the cam may be designed so the lift of a follower 316 riding thereon will be proportional to the azimuth change (ΔA) in the horizontal plane in accordance with Equation 7.

A rack 317 on the follower 316 rotates a pinion 318 which drives a shaft 319 an amount proportional to the azimuth change (ΔA). The shaft 319 drives one input of a differential 321, the other input of which is driven by the motor 247 through shaft 322. As was previously explained, the motor 247 is driven to rotate the gyro and the sight in azimuth to follow the target. Thus, this motor rotates an amount proportional to the present azimuth (A_o) of the target.

It will be apparent that the output of the differential 321 will be equal to the sum of the present azimuth (A_o) and the change in azimuth (ΔA), which is the angle of train (A. T.) of the guns. This angle of train may be transmitted to the guns in any suitable manner, by an electric data transmission system.

Since the cam 281 is translated in accordance with the elevation component (δE_s) of the prediction angle and rotated in accordance with the azimuth component (δA_s) of the prediction angle, the surface of the cam may be such that the lift of a follower 325 riding thereon will be proportional to the expression

$$\frac{1}{\sqrt{1 + \tan^2 \delta A_s \cos^2 \Delta E_s}}$$

The follower 325 translates a cam 326 that is rotated by a gear 327 which meshes with the elongated pinion 313. As was explained above, the pinion 313 is rotated an amount proportional to the sum of the present elevation (E_o) and the elevation component (δE_s) of the total prediction angle. Hence, the cam 326 is also rotated an amount proportional to the sum ($E_o + \delta E_s$).

The surface of the cam 326 may be laid out so a follower 329 riding thereon will be displaced an amount proportional to the future elevation (E_p) of the target in accordance with Equation 7. However, the angle (E_p) is relatively large, and since the cam is rotated in accordance with ($E_o + \delta E_s$), the sum of these two angles may be subtracted from the surface of the cam, whereby the follower will be displaced an amount equal to $E_p - (E_o + \delta E_s)$.

A rack 331 on the follower 329 rotates a pinion 332 which in turn rotates a shaft 333. The shaft 333 drives one input of a differential 334 an amount proportional to $E_p - (E_o + \delta E_s)$. The other input of the differential 334 is driven by a shaft 335 that is rotated through bevel gears 336

and 337 by the shaft 312. Since the shaft 312 is rotated in accordance with $(E_o + \delta E_s)$, the differential will add this sum to the rotation of shaft 333, whereby the output of the differential 334 will rotate a shaft 338 an amount proportional to the future elevation (E_p). The shaft 338 actuates a follow-up switch 339 to close contacts 341 and 342 to control the direction of rotation of a follow-up motor 343. The motor 343 acts through gears 344 and 345 to drive a shaft 346 an amount equal to the shaft 338, which is proportional to the future elevation (E_p).

In order to obtain the elevation angle to be transmitted to the guns, it is necessary to add a correction for super-elevation due to variations in the trajectory of the projectile in a vertical plane. The E_p follow-up motor 343 drives through the shaft 346, bevel gears 347 and 348, shaft 349, bevel gears 350 and 351 to rotate a shaft 352 and an elongated pinion 353 an amount proportional to the future elevation (E_p). Pinion 353 meshes with a gear 354 to rotate a cam 355 that is translated in accordance with the movements of a follower 356 on the cam 201.

Since for small prediction angles the future range (D_p) is approximately equal to the slant range (D_o) plus the slant range rate ($\dot{D}$) times the time of flight (t_p), the future slant range is approximately equal to a function of the slant range (D_o) and slant range rate ($\dot{D}$). Since the cam 201 is rotated in accordance with the slant range (D_o) and is translated in accordance with the slant range rate ($\dot{D}$), the surface of the cam may be laid out so the follower 356 riding thereon will be displaced an amount approximately proportional to the future range (D_p).

Since super-elevation varies in accordance with the future elevation (E_p) and the future range (D_p), the surface of the cam 355 is such that a follower 358 riding thereon is displaced an amount proportional to the super-elevation. A rack 359 carried by the follower 358 rotates a pinion 361 which drives a shaft 362 forming one of the inputs of a differential 363. The other input of the differential 363 is driven by the shaft 349 in accordance with the future elevation (E_p). It will be apparent that the output of the differential 363 will be the sum of the future elevation (E_p) and the super-elevation, which is the quadrant elevation (Q. E.). Quadrant elevation may be transmitted by a suitable data transmission system to control the position of the guns.

Equations 4 and 5 determine the elevation and azimuth components (δE_s and δA_s) of the prediction angle in accordance with the tangent function of these component angles. It has been found that the other functions may be substituted for these tangent functions to obtain the components of the prediction angle in a similar manner. When other functions of the component angle are used, it is also necessary to use other functions of slant range and slant range rate to ascertain a corrected time of flight that will give accurate prediction. For example, accurate predictions may be obtained by substituting sine functions for the tangent function of Equations 4 and 5.

Thus, the elevation component (δE_s) of the prediction angle may be said to be a function of the slant range, slant range rate, and elevation velocity of the target. Similarly, the azimuth component (δA_s) of the prediction angle may be determined as a function of the slant range (D_o), slant range rate ($\dot{D}$), and azimuth velocity (ΣA_s).

It will be apparent that the same quantities would be used as known values, that is, inputs to the predictor, and that similar values of the components would be obtained merely by substituting different cams in the mechanism corresponding to the functions used.

The prediction problem may also be approached empirically instead of mathematically. If a target is assumed to have a certain orientation, direction and velocity, its future position may be accurately calculated. Knowing the present position and the correct future position, it is possible to calculate the prediction angle. It is also possible to calculate the value of the function of slant range and slant range rate, that is, $f(D_o, \dot{D})$ that could be combined with a function of the prediction angle to give an accurate prediction.

By selecting different values for the orientation, direction, and velocity of the target, the varying prediction angle and the varying values of $f(D_o, \dot{D})$ may be tabulated. After making this tabulation, cams similar to cams 199, 208, and 209 may be designed to give accurate prediction.

Thus, it may be said that a function (F) of the prediction angle components (δE_s) and (δA_s) would equal a function (f) of slant range (D_o) and slant range rate ($\dot{D}$) multiplied by the target velocity. This may be expressed in the following manner:

$$F(\delta A_s) = f(D_o, \dot{D}) \Sigma A_s \quad (8)$$

and

$$F(\delta E_s) = f(D_o, \dot{D}) \Sigma E \quad (9)$$

These equations are similar to Equations 1 and 2, except that different functions of the components of the prediction angle are used and also the corrected time of flight is a different function of the slant range and slant range rate. Any functions may be used in these equations to obtain predictions and the function best suited for the purpose desired may be determined from tabulations of the results obtained.

In both of the intermediate range directors described, angular rates are used to obtain accurate predictions. These mechanisms are not subject to the error normally inherent in solutions based upon angular rate multiplied by time predictions. This error is eliminated by computing a corrected time of flight (t_p') as a function of slant range (D_o) and slant range rate ($\dot{D}$). Intermediate range directors embodying the present invention provide accurate predictions within the range limits for which they are designed and at the same time are much less complex than the long range directors.

In addition, prediction of future position is transmitted by the director to the guns almost immediately after the director operator begins tracking the target. As has been stated, it is essential for intermediate range operations, that the interval between sighting the target and obtaining accurate prediction be comparatively short.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

What is claimed is:

1. A director for controlling the fire of guns against moving targets comprising means for

setting into said director azimuth and elevation velocities of a target, a second means for setting into said director the range and the rate of change of said range, a third means actuated by said second means for computing time of flight as a function of said range and the rate of change of said range, a prediction mechanism actuated by the first mentioned means and said third means for multiplying respectively said azimuth and elevation velocities by said time of flight to obtain azimuth and elevation components of the predicted change in the position of said target, and another means responsive to the actuation of said prediction mechanism for converting said components into changes in gun aiming angles.

2. A director for controlling the fire of guns against moving targets comprising, a first device for setting into said director the azimuth and azimuth velocity of a target, a second device for setting into said director the elevation and elevation velocity of said target, a third device for setting into said mechanism the range of said target and the rate of change of said range, means actuated by said third device for instantaneously computing time of flight solely as a function of said range and said range rate, a predictor mechanism actuated by said first and second devices and said means for multiplying said azimuth and elevation velocities respectively by said time of flight to obtain azimuth and elevation prediction angles, means responsive to the actuation of said prediction mechanism for converting said prediction angles into changes in gun aiming angles, and means responsive to the actuation of said first and second devices and said last-named means for adding respectively said changes in gun aiming angles to the position of the target in azimuth and elevation to obtain gun aiming angles.

3. A director for controlling the fire of guns against moving targets comprising, a tracking member for following the movements of said target, a first device responsive to the movements of said member for setting into said director the azimuth and azimuth velocity of a target, a second device responsive to the movements of said member for setting into said director the elevation and elevation velocity of said target, a third device for setting into said target the range of said target and the rate of change of said range, means actuated by the third device for computing time of flight solely as a function of said range and said range rate, a mechanism in the director actuated by said first device and said means for computing in accordance with the azimuth velocity and said time of flight an azimuth prediction angle, a further mechanism in the director actuated by said second device and said means for computing in accordance with said elevation velocity and said corrected time of flight an elevation prediction angle, and means controlled by the respective mechanisms for converting said prediction angles into azimuth and elevation changes in gun aiming angles.

4. A predictor for determining the future position of a target, comprising a first device for introducing present azimuth (A_o) and azimuth rate (ΣA_{AH}), a second device for introducing present elevation (E_o) and elevation rate (ΣE), a third device for introducing present range (D_o) and range rate ($\dot{D}$), means actuated by said third device for computing a corrected time of flight ($t'p$) as a function of said range and range rate, a first mechanism responsive to said second device and said means for determining the eleva-

tion component (δE_s) of the prediction angle in accordance with the equation

$$\tan \delta E_s = \Sigma E t'p$$

5. A second mechanism responsive to said first and second devices and said first mechanism for determining the change in azimuth (ΔA) of said target in accordance with the equation

$$\tan \Delta A (1 - \tan E_o \tan \delta E_s) = \Sigma A H t'p$$

10 and a third mechanism responsive to said first and second mechanisms and said second device for determining the future elevation (E_p) of said target in accordance with the equation

$$E_p = \tan^{-1} [\tan (E_o + \delta E_s) \cos \Delta A]$$

15 5. A predictor for determining the future position of a target, comprising a first device for introducing present azimuth (A_o) and azimuth rate (ΣA_{AH}), a second device for introducing present elevation (E_o) and elevation rate (ΣE), a third device for introducing present range (D_o) and range rate ($\dot{D}$), means actuated by said third device for computing a corrected time of flight ($t'p$) as a function of said range and range rate, a first mechanism responsive to said second device and said means for determining the elevation component (δE_s) of the prediction angle in accordance with the equation

$$\tan \delta E_s = \Sigma E t'p$$

20 a second mechanism responsive to said first and second devices and said first mechanism for determining the change in azimuth (ΔA) of said target in accordance with the equation

$$\tan \Delta A (1 - \tan E_o \tan \delta E_s) = \Sigma A H t'p$$

25 a third mechanism responsive to said first and second mechanisms and said second device for determining the future elevation (E_p) of said target in accordance with the equation

$$E_p = \tan^{-1} [\tan (E_o + \delta E_s) \cos \Delta A]$$

30 and means responsive to said first device and said third mechanism for compensating said future elevation for superelevation in accordance with approximate future range and said future elevation.

35 6. A predictor for determining the future position of a moving target, comprising means for introducing the azimuth velocity (ΣA_s) in a slant plane and elevation velocity (ΣE) of a target, a second means for introducing the range (D_o) and a range rate ($\dot{D}$) of said target, means controlled by said second means for computing a corrected time of flight ($t'p$) as a function of said range and range rate, and a mechanism jointly actuated by the first-mentioned means and the last-mentioned means for computing the azimuth component (δA_s) of the prediction angle in accordance with the equation

$$\delta A_s = \tan^{-1} \Sigma A s t'p$$

40 and the elevation component (δE_s) of the prediction angle in accordance with the equation

$$\delta E_s = \tan^{-1} \Sigma E t'p$$

45 7. A predictor for determining the future position of a moving target, comprising means for introducing the azimuth velocity (ΣA_s) in a slant plane and elevation velocity (ΣE) of a target, a second means for introducing the range (D_o) and a range rate ($\dot{D}$) of said target, means controlled by said second means for computing a corrected time of flight ($t'p$) as a function of said

range and range rate, a mechanism actuated by the first-mentioned means and the last-mentioned means for computing the azimuth component (δA_s) of the prediction angle in accordance with the equation

$$\delta A_s = \tan^{-1} \Sigma A_s t' p$$

and the elevation component (δE_s) of the prediction angle in accordance with the equation

$$\delta E_s = \tan^{-1} \Sigma E_s t' p$$

and other means actuated by said mechanism for converting said component prediction angles to gun-aiming angles.

8. A predictor for determining the future position of a moving target, comprising means for introducing present azimuth (A_0) and azimuth rate (ΣA_s) in a slant plane and for introducing present elevation (E_0) and the elevation velocity (ΣE) of a target, a second means for introducing the range (D_0) and the range rate (D) of said target, means controlled by the second means for computing a corrected time of flight ($t' p$) as a function of said range and range rate, a mechanism jointly actuated by the first-mentioned means and the last-mentioned means for computing the azimuth component (δA_s) of the prediction angle in accordance with the equation

$$\delta A_s = \tan^{-1} \Sigma A_s t' p$$

and the elevation component (δE_s) of the prediction angle in accordance with the equation

$$\delta E_s = \tan^{-1} \Sigma E_s t' p$$

another means actuated by said mechanism for converting said prediction angles to gun-aiming angles, and further means actuated by the first mentioned and second means for compensating said gun-aiming angles for super-elevation in accordance with approximate future range and future elevation.

9. An apparatus for computing time of flight of a projectile solely from slant range comprising a shaft displaced according to slant range, another shaft displaced according to the rate of change of slant range, a three-dimensional cam adapted to be rotated by one of said shafts and translated by the other of said shafts a lift pin for the cam, the cam being laid out empirically to displace its lift pin in accordance with the time of flight for a given projectile for any combination of the displacement of said shafts.

10. An apparatus for computing time of flight solely from slant range comprising means displaced in accordance with slant range, means displaced in accordance with the rate of change of slant range, means actuated jointly by both of said means in accordance with their displace-

ments for computing time of flight empirically for a given projectile for any combination of the displacements of the first two means.

11. A predictor for determining the future position of a moving target including means for obtaining the angular rates of movement of the target in azimuth and elevation, a device for obtaining the range of said target and the rate of change of said range, means controlled solely by said device for computing the time of flight of a projectile as a function of said range and said range rate, and computing means actuated jointly by both means for obtaining predicted changes in the position of said target.

15 12. A predictor for determining the future position of a moving target including means for obtaining the angular rates of movement of the target in azimuth and elevation, a device for obtaining the range of said target and the rate of change of said range, means controlled solely by said device for computing the time of flight of a projectile as a function of said range and said range rate, and computing means jointly actuated by the first mentioned means in accordance with the respective angular rates of movement of the target in azimuth and elevation and by the second mentioned means in accordance with the time of flight for obtaining respectively the predicted changes in position of said target in azimuth and in elevation.

30 13. A predictor for determining the future position of a moving target including means for obtaining the angular rates of movement of the target in azimuth and elevation, a device for obtaining the range of said target and the rate of change of said range, means controlled solely by the device for computing the time of flight of a projectile as a function of said range and said range rate, and a computer including multiplying means jointly actuated by both of said means for obtaining predicted changes in the position of said target.
